UNITED STATES PATENT OFFICE

2,234,686

NEEDLE AND CLAMP THEREFOR

Charles T. Walter, Chicago, Ill., assignor to Industrial Patents Corporation, Chicago, Ill., a corporation of Delaware

Application January 2, 1940, Serial No. 312,160

11 Claims. (Cl. 99—256)

This invention relates to improvements in needles, particularly tubular needles of the artery or vein injector type.

One of the objects of the invention is to provide a tubular needle having improved means for facilitating its insertion within an end of a flexible, collapsible tube, for example, a vein or artery.

Another object of the invention is to provide a needle having improved means for binding around the outer wall of the needle, the end of the tube into which the needle is inserted.

Another object of the invention is to provide a tubular needle in which the clamping means may be fixedly adjusted longitudinally of the needle.

Other objects of the invention will be apparent from the description and claims which follow.

United States patents, No. 1,951,436 and No. 20,2,084,864, to Levi Scott Paddock, disclose methods of curing meats in which curing pickle is pumped under pressure through the circulatory system of the meat. Illustrative of the present invention, the device will be exemplified for curing meats according to the methods disclosed in the aforementioned patents. However, the device is equally adaptable as a surgical instrument as well as an instrument for the professional care of the dead. Other uses of the device will be apparent also.

In the drawing, like characters of reference are used to designate similar elements.

Figure 1 is a perspective view illustrating the device constructed in accordance with the present invention.

Figure 2 is another perspective view of the device.

Figure 3 is a side view showing the clamping jaws in locked position.

Figure 4 is another side view showing the needle about to be inserted within a vein of a cut of meat.

Needle 1 comprises enlarged nipple shank 2, the passage of which communicates with the passage of needle shank 3. Needle shank 3 is angularly ground at its free end to facilitate its insertion within the end of a collapsed tube. Shanks 2 and 3 may be machined as a unit, or as shown in the drawing, shank 3 may be pressed fit within shank 2.

Member 5 is substantially H-shaped. It comprises cross member 6 provided with central opening 7 and corresponding side members 8. Side members 8 at one each of their corresponding ends, as at 9, are provided with angularly

extended wings 10. Member 5 is mounted through opening 7 on needle 1. It may be rigidly affixed on needle 1 or, as shown in the drawing, it may be removably mounted for adjustment longitudinally of needle 1, but fixed against free movement, as by set screw 11.

Opposed clamping jaws 12 are pivoted, as at 13, within suitable openings provided in side pieces 8. Jaws 12 are pivoted for lateral movement from and toward the outer walls or periphery of needle 1 and engage needle 1 adjacent the free end of needle shank 3.

Jaws 12 are provided with integral arms 14 which extend rearwardly of pivot points 13. Toggle link 15 is secured intermediate arms 14 and adjacent the free ends thereof. Toggle link 15 comprises links 16 and 17 pivoted to one another at one each of their ends, as at 18, the link 16, at its opposite end, being pivoted to one of the arms 14, as at 19, and the link 17, at its opposite end, being pivoted to the other of the arms 14, as at 20. Obviously, one such link 15 is all that is required. However, as shown in the drawing, similar links may be employed to either side of arms 14.

Substantially T-shaped finger grip 21 is pivoted, as at 22, to wings 10, and, as at 18, to toggle link 15. When grip 21 is depressed, as at end 23, as shown in Figures 1 and 2, toggle link 15 is centrally drawn inwardly toward member 5 and simultaneously clamping jaws 12 are caused to spread to their outermost open position relative to needle 1. Concomitantly, when grip 21 is depressed, as at end 24, as shown in Figure 3, toggle link 15 is centrally moved outwardly away from member 5 and simultaneously jaws 12 are caused to close firmly against needle 1.

Jaws 12 are made of relatively rigid spring steel or other suitable material, and are made to positively engage the outer walls of needle 1 slightly ahead of toggle link 15 being moved to its straight line, outermost spreading position between arms 14. However, it will be noted that when grip 21 is depressed at end 24, movement of toggle link 15 is continued outwardly to a point slightly beyond the straight line position between arms 14, and also that further movement of toggle link 15 is prevented by abutment of end 24 against member 5. Thus, toggle link 15 serves to firmly and positively lock jaws 12 relative to the outer walls of needle 1.

Too, it will be seen that when end 23 is depressed, toggle link 15 in conjunction with pivots 13, serves to equally and positively maintain jaws 12, away from the walls of needle 1.

Movement of member 5, longitudinally of needle 1, previously described, provides similar movement of jaws 12 and thus, readjustment of jaws 12 relative to the end of needle 1, following 5 sharpening or regrinding of the end of needle 1.

Figure 4, shows the jaws 12 in open position, and needle 1 in the course of being inserted within the end 25 of vein 26, which previously has been dissected, by an operator not shown, 10 out of meat cut 27. This figure shows also, flexible tube 28 firmly affixed, as by collar 29, to free end 30 of nipple shank 2, for the carriage of fluid to needle 1.

I claim:

- 15 1. In combination with a hollow needle, clamping jaws and means including a toggle link operatively associated with the jaws and adapted for positively locking the jaws against the outer walls of the needle.
- 20 2. In combination with a hollow needle, clamping jaws and means including a toggle link operable between the jaws to positively lock the jaws against the outer walls of the needle.
- 25 3. In combination with a hollow needle, clamping jaws provided with toggle link locking means.
- 30 4. In combination with a tubular needle, clamping jaws and a toggle link operable between the jaws to positively lock the jaws against the outer periphery of the needle.
- 35 5. In combination with a tubular needle, a pair of clamping jaws pivotally connected with the needle, each of the jaws having a rigid arm extended rearwardly of its pivot point, a toggle link connecting the pair of arms and means controlling the toggle link to open and close the jaws relative to the needle.
- 40 6. In combination with a tubular needle, a pair of clamping jaws pivotally connected with the needle, each of the jaws having a rigid arm extended rearwardly of its pivot point, a toggle link connecting the pair of arms and means controlling the toggle link to open and close the jaws relative to the needle and to positively lock the jaws substantially against the outer periphery of the needle.
- 45 7. In combination with a tubular needle, a pair of clamping jaws pivotally connected with the

needle, each of the jaws having an integral arm extended rearwardly of its pivot point, a separate link pivotally connected with each of the arms and with each other and means controlling the links to open and close the jaws relative 5 to the needle and to positively lock the jaws substantially against the outer periphery of the needle.

8. In combination with a tubular needle, a member removably affixed on the needle for longitudinal adjustment and providing a pair of lateral pivot points equally spaced from the needle, a clamping jaw pivotally connected with the member at each of the pivot points, each of the jaws having an integral arm extended rearwardly 10 of its pivot point, a toggle link connecting the arms and means functionally engaging the member and toggle link and operable to control the toggle link to open and close the jaws relative 15 to the needle and to positively lock the jaws substantially against the outer periphery of the needle.

9. In combination with a tubular needle, pivoted clamping jaws provided with integral rearwardly extending arms, a toggle link spreadable 20 between the arms to close the jaws relative to the needle, and means operable to move and to hold the toggle link slightly past its straight line position to positively lock the jaws substantially 25 against the outer wall of the needle.

10. In combination with a tubular needle, pivoted clamping jaws provided with integral rearwardly extending arms, a toggle link spreadable between the arms to close the jaws relative to the needle, and means operable to move and to hold the toggle link slightly past its straight line position to positively lock the jaws substantially 30 against the outer wall of the needle, the needle at its free end being beveled to facilitate its insertion into the end of a tube.

11. In a tubular needle including clamping jaws movable laterally relative to the outer wall of the needle, said jaws being mounted upon means removably affixed for longitudinal adjustment 35 longitudinally on the handle.

CHARLES T. WALTER.

CERTIFICATE OF CORRECTION.

Patent No. 2,234,686.

March 11, 1941.

CHARLES T. WALTER.

It is hereby certified that error appears in the printed specification of the above numbered patent requiring correction as follows: Page 2, second column, line 45, claim 11, for the word "handle" read --needle--; and that the said Letters Patent should be read with this correction therein that the same may conform to the record of the case in the Patent Office.

Signed and sealed this 15th day of April, A. D. 1941.

Henry Van Arsdale,
Acting Commissioner of Patents.
